CENTERING DEVICE FOR EXTRUDING
PRESSESGuy H. Bradley, Pleasant Ridge, Mich., assignor
to Wolverine Tube Company, Detroit, Mich., a
corporation of Michigan

Application December 14, 1936, Serial No. 115,854

5 Claims. (Cl. 207—1)

This invention relates generally to extruding presses and refers more particularly to improved means for centering a blank or a billet in the holder of the press prior to the extruding operation.

In accordance with this invention, a billet or a blank is placed in a holder or retainer in seating relation to the extruding die and is upset to not only effect an intimate contact of the lower end 10 of the billet with the extruding die, but to also bring the side surfaces of the billet in intimate contacting relation with the inner surfaces of the retainer. Thus, the billet is accurately centered in the retainer on the extruding die, and shifting movement thereof during the extruding operation is effectively eliminated.

It is one of the principal objects of this invention to expedite and appreciably simplify the means for upsetting the billets to center the latter with reference to the extruding die, and the several novel features of this means will be made more apparent as this description proceeds, especially when considered in connection with the accompanying drawings, wherein:

Figure 1 is a fragmentary side elevational view partly in section of an extruding press embodying a centering device constructed in accordance with this invention;

Figure 2 is a plan view of a portion of the centering device shown in Figure 1;

Figure 3 is a cross sectional view taken substantially on the plane indicated by the line 3—3 of Figure 2;

Figure 4 is a sectional view taken substantially on the plane indicated by the line 4—4 of Figure 2; and

Figure 5 is a sectional view taken substantially on the plane indicated by the line 5—5 of Figure 2.

In general, a blank or billet A, which is preferably preheated to a predetermined temperature, is inserted into a holder or retainer B in seating relation with an extruding die C having a central opening therethrough and having a tapered seat surrounding the opening. After the billet A is placed in the retainer B on the extruding die C, the centering device D is swung to its operative position with respect to the retainer and the billet is upset by this device. As a result of the upsetting operation, the sides of the billet A are in intimate contacting relation with the inner surfaces of the retainer and the lower end of the billet is deformed to intimately engage the tapered seat on the extruding die C. Consequently, the billet is accurately centered in

the retainer B and lateral shifting movement of the billet, during the extruding operation, is prevented. Upon completion of the upsetting operation, the billet is pierced by the piercing punch E, and the metal of the billet is extruded through the central opening in the die C around the piercing punch E to form the tube.

The centering device D is shown in Figure 1 as hingedly connected to the frame 10 of the press for swinging movement in a horizontal plane from an inoperative position, to one side of the piercing punch E, to an operative position above the retainer B in registration with the latter. In detail, the centering device comprises an arm 11 having vertically spaced bearings 12 at 15 the outer end thereof rotatably supported on a vertical shaft 13 having the extremities thereof secured to the frame 10 by means of the brackets 14. The inner end of the arm 11 carries the upsetting tool assembly 15 and the elevation of 20 the arm on the shaft 13 is determined to provide for engagement of the annular spacer 16 with the upper end of the retainer B when the tool assembly is swung to the position thereof shown in Figure 1. In this connection, it will be noted 25 that the lower bearing 12 of the arm 11 rests upon a collar 17 pinned to the shaft 13 for movement with the latter as a unit and adapted to be vertically adjusted by means of a set screw 18 threadedly secured in the bottom bracket 14 for 30 engagement with the lower end of the shaft 13. Thus, adjustment of the set screw 18 varies the vertical position of the shaft 13 and, accordingly, varies the elevation of the upsetting tool assembly 15 relative to the retainer B.

The upsetting tool assembly 15 comprises a tubular sleeve 19 secured to the inner end of the arm 11 with its axis extending parallel to the axis of swinging movement of the arm and adapted to assume a position in coaxial relationship 40 with the well 20 in the retainer when the arm is swung to its operative position shown in Figure 1. Upon reference to Figure 2, it will be noted that the inner end of the arm 11 is provided with a vertically extending transversely curved member 21 having a radius of curvature corresponding to the radius of the outer surface of the sleeve 19 and is welded, or otherwise permanently secured to this surface of the sleeve. It will be noted from Figure 3 that the lower end of the sleeve extends 45 below the arcuate portion 21 of the arm and is permanently secured to a plate 23 centrally apertured to receive the sleeve. In the operative position of the upsetting tool assembly 15, the plate is supported upon the retainer B by means 50 55

of the annular spacer 16 integrally connected to the underside of the plate 23.

5 The sleeve 19 forms a vertical guide for the tool carrying plunger 24 having an axially extending bore 25 therethrough and having an upsetting tool 26 removably secured to the lower end thereof by means of a stud 27. The bore 25 is of sufficient dimension to freely receive the piercing punch E, and the upper end of the 10 plunger 24 is provided with a tapered seat 28 for engagement with the correspondingly tapered lower end portion of an enlargement 29 on the piercing punch E.

15 The piercing punch E is actuated by a vertical- ly movable ram 30 slidably supported upon the machine frame 10 and actuated by fluid pressure means designated generally by the reference character 31. The arrangement is such that when the upsetting tool assembly 15 is swung to 20 its operative position with respect to the billet retainer B and the ram 30 is lowered by the means 31, the enlargement 29 on the piercing punch engages the seat 28 on the upper end of the plunger 24. Upon continued downward move- 25 ment of the piercing punch by the ram 30, the plunger 24 is moved by the piercing punch down- wardly in the sleeve 19, and the upsetting tool 26 is telescoped within the well 20 of the retainer B into engagement with the billet A. The lower 30 end of the tool 26 is frusto-conical in shape and functions to upset the billet A as the ram 30 continues its downward movement. Inasmuch as the lower end portion of the tool 26 has a sliding fit with the internal surface of the well 20 in the 35 retainer B, metal from the billet is prevented from flowing upwardly and, as a consequence, is forced outwardly and downwardly into intimate contacting relation with the sides of the well and the top surface of the extruding die C. This results 40 in accurately centering the billet relative to the extruding die C and prevents lateral shifting of the billet in the well 20.

45 Referring again to Figure 3 of the drawings, it will be noted that provision is made for automatically withdrawing the upsetting tool 26 from the well 20 when the ram is returned to its upper- most position. This is accomplished in the pres- 50 ent instance by interposing a plurality of springs 32 between the plate 23 secured to the fixed sleeve 19 and the vertically reciprocable plunger 24. In detail, a plurality of vertically extending rods 33 are secured at their lower ends to the plate 23 in concentric relation to the axis of the sleeve 19. The axes of the rods are parallel to the axis of 55 the sleeve 19, and the upper ends of the rods slidably engage a plate 34 secured to the upper end of the plunger 24. The springs 32 surround the rods 33 between the plates 23 and 34, with the result that these springs are compressed by 60 the plunger 24 as it is moved downwardly relative to the sleeve 19 to upset the billet A. It will, of course, be understood that when the 65 piercing punch E is returned to its uppermost position by the ram 30, the springs 32 function to move the plunger 24 upwardly and withdraw the upsetting tool 26 from the well 20. It will be 70 noted from Figure 2 that the rods 33 are spaced at equal distances from each other circumferentially of the sleeve 19, and this results in a direct uniform axial movement of the plunger 24 relative to the sleeve 19 in an upward direction.

75 Upon reference to Figure 4 of the drawings, it will be noted that the stroke of the piercing punch E need not be sufficient to clear the plunger 24 when the latter is either swung into or out of

registration with the retainer B. As shown in this figure, the leading side of the plunger 24 is provided with a slot 35 therethrough having a width slightly greater than the diameter of the piercing portion of the punch and having a length 5 determined to permit the plunger to be swung out of registration with the retainer B when the piercing punch is moved to the extent required to disengage the upsetting tool 26 from the well 20 of the retainer B. The above arrangement re- 10 duces the stroke of the ram 30 to the minimum and this is desirable in that it offers the possibility of reducing the weight, cost and size of the apparatus.

15 In Figure 5 of the drawings, I have shown means for accurately positioning the upsetting tool assembly 15 in operative relation to the billet retainer B prior to the upsetting operation. In detail, a bracket 36 is secured to the bottom of the sleeve 19 and extends laterally outwardly from 20 the sleeve. The outer end of the bracket is pro- 25 vided with a downturned flange portion 37 car- rying an adjusting screw 38 having a head portion 39 adapted to engage one side of the billet retainer B when the arm carrying the upsetting tool assembly 15 is swung to its operative position. The screw 38, of course, may be readily adjusted to insure accurately aligning the guide sleeve 19 of the upsetting tool assembly with the well 20 containing the billet A. 30

Thus, from the foregoing, it will be apparent that I have provided a relatively simple and inexpensive tool assembly capable of being readily moved from an inoperative position out of registration with the billet retainer to an operative 35 position in registration with said retainer. It will also be apparent that I have provided means spaced at equal distances around the axis of the upsetting tool for uniformly withdrawing the latter from the well of the retainer in dependence 40 upon return movement of the actuating ram. This feature is of importance in that it not only prevents binding of the relatively movable parts, but permits accurately fixing the elevation of the arm 11 carrying the upsetting tool assembly. 45

What I claim as my invention is:

1. Apparatus for centering blanks in retainers of extrusion presses having a punch supported for movement into and out of the retainer, comprising an upsetting plunger supported for swinging movement from an inoperative position 50 to a position between the punch and retainer in registration with the latter, said upsetting plunger having a slot through the leading side for receiving the punch upon being swung into registration with the retainer and being supported for movement by the punch into engagement with the blank in the retainer, and spring means spaced around the plunger tensioned by movement of the punch into the retainer and effective upon return movement of the punch to withdraw the plunger from the retainer. 55

2. Apparatus for centering blanks in retainers of extrusion presses, comprising an arm hingedly mounted for swinging movement from an inoperative position to an operative position, an upsetting plunger carried by the arm in a position to register with the retainer in the operative position of the arm, a spacer element on said arm and engageable with the retainer to prevent 65 cocking of the arm, said spacer element surround- 70 ing said plunger and being spaced radially therefrom, and means for moving the plunger into and out of engagement with the blank in the retainer. 75

3. Apparatus for centering blanks in retainers of extrusion presses, comprising an arm hingedly mounted for swinging movement from an inoperative position to an operative position, an upsetting plunger carried by the arm in a position to register with the retainer in the operative position of the arm, a spacer element on said arm and engageable with the retainer to prevent cocking of the arm, said spacer element surrounding said plunger and being spaced radially therefrom, and means mounting the plunger on the arm for movement relative to the latter into and out of engagement with the blank in the retainer.
4. Apparatus for centering blanks in retainers of extrusion presses, comprising an arm, an upsetting plunger mounted on the arm for movement relative to the latter into and out of engagement with the blank in the retainer, means hingedly supporting the arm to permit swinging the plunger into and out of registration with the retainer, a spacer element on said arm and engageable with the retainer to prevent cocking of the arm, said spacer element surrounding said

plunger and being spaced radially therefrom, and yieldable means spaced equal distances from each other around the plunger for withdrawing the latter from the retainer.

5. Apparatus for centering blanks in retainers of extrusion presses having a reciprocable member, comprising an arm, an upsetting plunger mounted on the arm for movement relative to the latter by said member into engagement with the blank in the retainer, means hingedly supporting the arm to permit swinging movement of the plunger into and out of registration with the retainer, a spacer element on said arm and engageable with the retainer to prevent cocking of the arm, said spacer element surrounding said plunger and being spaced radially therefrom, and a plurality of springs carried by the arm in spaced relation to each other around the plunger and acting on the latter when the member is in its return movement to withdraw the plunger from the retainer.

GUY H. BRADLEY.
